WRINGER

Clifton C. Cammack, Algonquin, Ill., assignor to
Barlow & Seelig Manufacturing Company, Rip-
on, Wis., a corporation of Delaware

Application August 9, 1941, Serial No. 406,111

8 Claims. (Cl. 68—253)

The invention relates to wringers of the type used in connection with household laundry machines, and the general aim of the invention is to provide, in a wringer of this nature, new and improved means for quickly discontinuing the drive to the wringer rolls as an incident to release of operative pressure between the rolls.

An object of the invention is to provide a wringer structure embodying improved means of simple, efficient construction and operation for stopping the roll drive independently of the reversing gearing mechanism and as an incident to the quick-release of the wringer head and roll pressure effected by actuation of the safety release mechanism.

More specifically stated, an object is to provide in a wringer structure, which includes separable frame sections adapted to be moved into operative association, wringer rolls arranged to be tensioned when the frame sections are releasably latched together, and drive means for the wringer rolls controlled by manually operable reversing gearing, new and improved means for discontinuing the roll drive ahead of the reversing gearing including endwise engageable drive shaft sections normally urged to disengaged position and adapted to be drivingly coupled as an incident to movement of the frame sections into operative association, the relationship being such that the drive to the reversing gearing is immediately interrupted by relative endwise movement of the shaft sections when the frame sections are released in an emergency.

Other objects and advantages will become apparent in the following description and from the accompanying drawings in which:

Figure 1 is a side elevation of a wringer embodying the features of the invention and having certain of the parts broken away to show the underlying construction and showing in dotted outlines the head section in its released position.

Fig. 2 is a fragmentary horizontal sectional view on an enlarged scale taken along the line 2—2 of Fig. 1.

Fig. 3 is a fragmentary vertical section through the right hand end of the wringer showing the drive mechanism in engaged position.

Fig. 4 is a sectional view similar to Fig. 3 showing the drive in its disengaged position.

Fig. 5 is a view similar to Fig. 3 showing the head in operative association with the frame and the drive mechanism immediately prior to engagement.

Fig. 6 is a detailed sectional view taken along the line 6—6 of Fig. 3.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

In general, the exemplary form of wringer structure illustrated herein embodies a frame comprised of a fixed or base section 20 (Fig. 1) having a lower member and spaced upstanding 15 end members 21 and 22 arranged to support thereon a movable section or head 23. The end members 21 and 22 are in the form of channel-shaped side stiles which receive and support the bearings for a pair of cooperating wringer rolls 20 24 and 25. Thus, half bearings 26 and 27 for the shaft 28 of the lower wringer roll 24 and bearing blocks 29 and 30 for the shaft 31 of the upper roll 25 are disposed slidably in the side stiles. The end wall of one side stile (in this instance the right hand stile 22) is slotted, as at 32, to permit the corresponding end of the shaft 28 to extend therethrough for connection with the roll driving mechanism. Rigid with the bearing blocks 29 and 30 are carrying plates 33 and 34 which extend 30 above and beyond the upper roll and the bearing blocks to receive through slots 35 the respective opposite ends of a leaf spring 37 located within the head and above the upper roll 25. Operative roll pressure is imposed on the rolls by such 35 means as a tension screw 38 threaded in the head for manual adjustment by a knob 39 and bearing on the central portion of the leaf spring 37.

A wringer gear box 45 is rigidly secured in this embodiment to the right hand side stile. The 40 wringer head 23 is an inverted, channel-shaped member having closed ends and the head is dimensioned to extend longitudinally across the side stiles 21 and 22 and over the upper surface of the gear box. The head in this instance is pivotally secured at one end to the gear box for vertical swinging movement into and out of assembled relation with the base section of the frame. Thus, the right hand end of the head has ears 44 to receive a horizontal pivot pin 46 fixed in the gear box.

At the left hand end of the head and frame, means is provided for moving the head section from its raised, inoperative position toward the frame section and for latching the head in operative association with the frame. This means in

the present instance comprises a toggle linkage including an actuating member or reset lever 47 pivotally supported, as at 48, on the left end of the head, and formed for convenient manipulation by the operator. A link 49 is pivotally supported at one end, as at 50, in ears 51 on the end member 22 and at its other end, as at 52, on an intermediate portion of the reset lever 47. The relationship is such that upon movement of the reset lever 47 from its disengaged or raised position, as shown in dotted outlines in Fig. 1, inwardly and downwardly to its latched position, along the side stile as shown in full outlines, the head is correspondingly moved about its pivot point 46 toward the frame and into operative engagement therewith to tension the leaf spring 37. During such movement the toggle linkage 47, 49 moves just past a dead center alinement of the pivot points 48, 50 and 52. In this position, the head is latched, the rolls are tensioned and remain tensioned until the latch mechanism is released.

The quick release mechanism in the present instance comprises a pair of impact bars 53 supported for movement in slots 54 in the head to engage projections 55 on the actuating member 41. Springs (not shown) yieldably urge the impact bars to a raised position in which the bars extend outwardly from the head for convenient manipulation by the operator. In an emergency, depression of either bar causes the projections 55 on the actuator to move the actuating member 41 outwardly and release the toggle linkage from its dead center position, permitting the head to "jump" to its inoperative position, as shown in dotted outline in Fig. 1.

In the present structure the wringer drive mechanism (Fig. 1) embodies a drive shaft 57 rotatably housed in a sleeve 58 supported by and depending from the gear box 45. Power to drive the wringer is transmitted to the shaft 57 by a suitable wringer drive shaft (not shown). A pair of spaced gears 60 and 61 connected by an intermediate clutch shifting element or collar 62 are slidably splined on the drive shaft for rotation therewith. The extended end of the lower wringer roll shaft 28 is connected through a universal coupling 63 with a crown gear 64 journaled, as at 65, in the gear box for selective engagement by the gears 60 and 61.

The means for shifting the clutch member 62 with its gears 60, 61 from central, neutral position to selectively engage the gear 60 or 61 with the crown gear 64 includes an actuator shaft 66 journaled on the gear box having an operating handle 67 at its outer end. The inner end of the actuator shaft 66 has a crank plate 68 which carries eccentrically a pin 69 engaged in an annular groove 70 formed in the clutch member 62. The crank plate 68 may be squared at its edges for engagement by a flat spring 71 (Fig. 1) to define the "neutral," "forward" and "reverse" positions of the reversing gearing mechanism.

In such a wringer construction I have provided improved means for automatically and instantaneously discontinuing the drive to the rolls independently of the reversing gearing mechanism and as an incident to emergency release of the wringer head. The invention provides means dependent on the operative association of the wringer head and base sections for holding separate coaxially alined and relatively axially movable sections of the drive shaft drivingly engaged. The engagement is automatically discontinued upon release of the head and frame sections, irre-

spective of the position of the reversing gearing mechanism.

An exemplary form of the drive interrupting means is best shown in Figs. 3, 4 and 5. The drive shaft 57 is a sectional member comprised of upper and lower sections 72 and 73, respectively. The upper section includes the splined connection with the clutch collar 62 and above the splined portion extends through an upper bearing 74 on the gear box. The lower section 73 is journaled in the sleeve 58 by spaced bearings 73a and is held against axial movement by a collar 75 pinned on its upper end and by such means as a split ring 75a on the shaft section for engagement with the under side of the lower bearing 73a. The collar 75 extends beyond the upper end of the lower section 73 slidably to receive and support the lower end of the upper section 72 in axial alinement with the lower section 73. The lower and upper shaft sections 72, 73 are releasably coupled by complementary clutch elements 76 which are disengageable upon endwise or axial movement of the shaft section 72 upwardly (compare Figs. 3 and 4). It is to be noted that the shaft section 72 is movable to engage and disengage the drive independently of the position of the clutch 62 thereon.

Pivotedly supported, as at 77, at the upper side of the gear box, is a bracket 78 having a yoke 79 engaged in a groove 80 formed on the projecting upper end of the shaft sections 72 above the bearing 74. A coil spring 81 bearing between the gear box and the bracket 78 acts through the bracket 78 and yoke 79 to urge the shaft section 72 to a raised position in which the clutch elements 76 are disengaged. Carried on the underside of the head section above the bracket 78 is a depending element 82 adapted for engagement with a leaf spring 83 secured on the bracket to project therefrom for engagement with the upper end of the shaft section 72. Upon depression of the head into its operative position on the frame, the bearing element 82 depresses the bracket 78 against the forces of the springs 81, 83 to shift the shaft section 72 axially downwardly into engagement with the lower section 73. In the event that the complementary parts of the clutch element 76 are not in alinement, the leaf spring 83 will yield (as shown in Fig. 5), sufficient lost motion being provided between the yoke 79 and groove 80 to permit depression of the bracket. Upon initiation of the wringer drive thereafter, the clutch elements will be moved into alinement to permit the shaft section 72 to be snapped into engagement by the force of the leaf spring 83, thereby completing the drive to the wringer rolls.

The spring 81 is preferably of sufficient force to overcome the weight of the wringer head assembly 23 independently of the force of the roll tensioning spring 37 so that upon release, the head is raised to a proper height to allow disengagement of the clutch elements 76.

It will be apparent from a consideration of the foregoing that I have provided an improved roll stop mechanism which is completely independent of the reversing gearing mechanism and which is effective to discontinue the roll drive immediately upon release of roll pressure. The roll stop mechanism is automatically engageable upon setting of the head. It will be apparent further, that the roll stop of the present invention is characterized by extreme simplicity and a relatively few number of parts, rendering its manufacture convenient and of low cost. Accordingly, the device may

be installed in wringers of even the cheapest construction.

I claim as my invention:

1. In a wringer having separable frame sections and wringer rolls adapted to be placed under operative pressure when said frame sections are operatively associated, the combination of a drive shaft, an axially engageable and disengageable driven member coaxially aligned with said shaft, manually disengageable means for drivingly connecting said driven member and said rolls, spring means tending to urge said driven member axially to a disengaged position, and yieldable means engageable with said driven member by movement of said frame sections into operative association for urging said driven member into engagement with said shaft.

2. In a wringer having separable frame sections and wringer rolls adapted to be tensioned upon movement of said frame sections into operative association, the combination of a drive shaft, an axially movable shaft section coaxially aligned with said drive shaft, clutch elements on the adjacent ends of said drive shaft and shaft section respectively engageable and disengageable upon axial movement of said shaft section toward and away from said drive shaft, spring means tending to urge said shaft section axially away from said drive shaft to disengage said clutch elements, means for urging said shaft section toward said drive shaft to engage said elements upon movement of said frame sections into operative association, said last-mentioned means being yieldable to permit centering of said elements and further engaging movement of said shaft section upon power rotation of said drive shaft, and means drivingly engageable between said shaft section and said rolls irrespective of the axial position of said shaft section.

3. A wringer including, in combination, a frame having a separable head, quickly releasable latch means for holding said head in operative engagement with said frame, wringer rolls journaled in said frame, means for applying an operating pressure to said rolls when said head is operatively associated with said frame, a drive shaft having a separate coaxial section slidable axially relative to said shaft, clutch elements on the adjacent ends of said shaft and section engageable and disengageable by movement of said section toward and away from said shaft respectively, spring means urging said section away from said shaft, a driven gear element on one of said wringer rolls, a pair of driving gear elements splined on said shaft section for sliding movement as a unit into selective engagement with said driven element to drive said rolls in one direction or the other, and means for shifting said section toward said drive shaft upon movement of said head toward said frame, said last-mentioned means including an element yieldable to permit operative engagement of said head with said frame when said clutch elements are not centered and further engaging movement of said shaft section upon centering of said clutch elements by rotation of said drive shaft, said last-mentioned means being positioned to permit movement of said shaft section away from said shaft under the influence of said spring means upon release of said latch means and separation of said head.

4. A roll stop device for a wringer embodying a separable head, wringer rolls, and quick release means operable to hold the wringer rolls under or release them from an operative pressure thereon, having in combination drive means for the

wringer rolls including relatively axially movable shaft sections, means drivingly connecting said shaft sections when said sections are in one relative position, means normally urging said shaft sections toward a relative position in which the connecting means is disengaged, and means controlled by the head for yieldably engaging the shiftable one of said shaft sections when said wringer rolls are held under operative pressure to hold said sections in the position thereof in which said connecting means is engaged.

5. In a wringer having a frame, a separable head, wringer rolls, and quick release means for holding said frame and head assembled against separating movement with said rolls operatively associated, drive means for said rolls including separable drive shaft sections having connecting means engageable and disengageable by axial movement of one shaft section relative to another shaft section, and means movable by said head to engage the movable one of said shaft sections when the head and frame are assembled for holding the movable shaft section in its axial position in which said connecting means is engaged, said means also having an engagement with said movable shaft section for shifting said movable shaft section to disengage said connecting means when the head separates from said frame.

6. In a wringer having a frame, a separable head, wringer rolls, and quick release means for holding said frame and head assembled against separating movement with said rolls operatively associated, drive means for said rolls including separable drive shaft sections having connecting means engageable and disengageable by axial movement of one shaft section relative to another shaft section, the axially movable section having an end positioned adjacent to said head, means engageable with the adjacent end of said axially movable section to thrust it axially when the head and frame are assembled and thereafter hold it in the axial position thereof in which said connecting means is engaged, and means for pulling said movable shaft section axially to disengage said connecting means when the head separates from said frame.

7. In a wringer having a frame including a separable head, wringer rolls supported by said frame and quick release means for connecting said head to said frame against relative separating movement, the rolls being operatively associated when the head and frame are so connected, the combination of drive means for said rolls including an axially movable drive shaft section having an end thereof disposed adjacent to said head, the direction of the axial movements of said shaft section being substantially the same as the movements of said head relative to said frame, and means pivotally mounted on said frame and engaging the end of said axially movable shaft section, said means being movable by said head in the operation of connecting the head and frame to shift said shaft section axially in one direction and being movable to shift said shaft section in the opposite direction when the head separates from the frame, and drive connecting means respectively engageable and disengageable by the aforesaid axial movements of said shaft section.

8. In a wringer having a frame including a separable head, wringer rolls supported by said frame and quick release means for connecting said head to said frame against relative separating movement, the rolls being operatively associated when the head and frame are so connected,

the combination of drive means for said rolls including an axially movable drive shaft section having an end thereof disposed adjacent to said head, the direction of the axial movements of said shaft section being substantially the same as the movements of said head relative to said frame, a member pivoted on said frame, means connecting said member with the end of said shaft section for translating the swinging movement of said member into axial movements of 10

said shaft section, resilient means acting on said member for urging it and said shaft section to one position, means on said head engaging said member for urging it and said shaft section to an opposite position in the act of connecting said head to said frame, and a driving connection to said shaft section established when said shaft section is in the last-mentioned position thereof.

CLIFTON C. CAMMACK.
